(57) **CLAIM**

I claim the ornamental design for a pint glass light, as shown and described.

DESCRIPTION

FIG. 1 is a perspective view of a pint glass light embodying the invention.

FIG. 2 is a left side view of the pint glass light shown in FIG. 1.

FIG. 3 is a right side view of the pint glass light shown in FIG. 1.

FIG. 4 is a front view of the pint glass light shown in FIG. 1.

FIG. 5 is a rear view of the pint glass light shown in FIG. 1.

FIG. 6 is a top view of the pint glass light shown in FIG. 1.

FIG. 7 is a bottom view of the pint glass light shown in FIG. 1; and,

FIG. 8 is a perspective view of the pint glass light shown in FIG. 1, illustrating the pint glass light as lit.

The broken lines showing the environment form no part of the claimed design.
